UNITED STATES PATENT OFFICE.

JOHN MERTON DENSON, OF CORTLAND, NEW YORK.

PISTON-PUMP.

965,132.

Specification of Letters Patent. Patented July 19, 1910.

Application filed October 6, 1909. Serial No. 521,292.

To all whom it may concern:

Be it known that I, JOHN MERTON DENSON, of Cortland, in the county of Cortland, in the State of New York, have invented 5 new and useful Improvements in Piston-Pumps, of which the following, taken in connection with the accompanying drawings, is a full, clear, and exact description.

This invention relates to certain improvements 10 in double acting piston pumps, involving the use of specific forms of oscillatory valves operating intermittently at the end of each stroke of the piston, through the medium of connections with the driving 15 mechanism for controlling the inlet and outlet of the water or other fluid, to and from opposite ends of the cylinder.

The main object is to increase the utility, 20 durability and range of use of this class of pumps and at the same time to reduce to a minimum the friction of the fluent through the pump and particularly through the valves. In other words, I have sought to produce a combined suction and force pump 25 capable of pumping liquid, air or gases or for dredging purposes and at the same time reducing the liability of rendering the pump inoperative by excessive frictional wear or clogging the valves.

30 Other objects and uses relating to specific parts of the pump will be brought out in the following description:

In the drawings: Figures 1 and 2 are respectively a top plan and a side elevation 35 of a pump, involving the various features of my invention, the cylinder and right hand valve in Fig. 2 being shown in section. Fig. 3 is a horizontal sectional view taken on line 3—3 Fig. 2. Figs. 4 and 5 are vertical sectional views taken respectively on lines 4—4 40 and 5—5, Fig. 1.

In carrying out the objects stated, I provide a cylinder —1— with a movable piston —2— and opposite tubular end heads —3— 45 and —3'—, which latter are deflected in the same direction at substantially right angles to the cylinder and are suitably secured to the central portions of transversely extending valve casings —4— and —4'—. These 50 valve casings and valves therein, presently described, are of the same construction and therefore the same description applies to both valve mechanisms. Each valve casing —4— is provided in one side with a central 55 port —5— which communicates with the adjacent end of the cylinder —2—. The oppo-

site side of this valve casing is provided with an inlet port —6— and an outlet port —6'—, said ports being located near the ends and equi-distant from the center of the valve casing. The ports —6— at one end of the valve casings are connected by a suction pipe —7—, having a central branch —8— adapted to be connected to the source of liquid supply. The outlet ports —6'— at the opposite end of the valve casings are connected together by a pipe —7'— having a central outlet pipe —10—.

In some instances I may prefer to use an air chamber —11— connected to the outlet pipe —7'—, in which air may be compressed by the outflowing liquid, during the compression stroke of the piston, so as to maintain a more continuous flow of the liquid through the outlet.

Suitable oscillatory valves —12— are fitted within their respective casings —4— and —4'—. Each valve is provided with axially projecting studs —13— and —13'— which are journaled in suitable bearings 80 —14— in the casing heads, as —15— and is formed with straight parallel passages —16— and —16'— extending diagonally and diametrically therethrough, said passages being separated by a partition —17—. 85 The distance from center to center of the ends of the passages, parallel with the axis, is substantially equal to half the distance from center to center of the ports —6— and —6'— and is also equal to the amount of 90 offset of one end of each passage from the opposite end so that when the valve is shifted to one of its positions, one end of one of the diagonal passages is registered with the port —5—, while the opposite end of the 95 same passage is registered with one of the diagonally opposite ports and when the valve is shifted to the other extreme position the other diagonal passage connects the port —5— with the other diagonal opposite 100 port. In other words the inner ends of the passages —16— and —16'— are diametrically opposite to each other and in the same transverse plane as the port —5—, while the outer ends of said passages nearest the 105 end of the valve are disposed in the same transverse planes, respectively, as the ports —6— and —6'—, thereby causing the inner ends of the passages —16— and —16'— to alternately register with the port —5— and their outer ends to alternately register with the ports —6— and —6'—, as the valve is

rotated a half turn from one position to the other.

Any suitable means may be employed for reciprocating the piston, such means consisting, in this instance, of a driving shaft 5 —18— carrying a pulley —19— and pinions —20— which mesh with suitable gears —21—, the latter being eccentrically connected by a connecting rod —22— to a cross 10 head —23—, to which the outer end of the piston rod, as —24—, is secured. The pulley —19— may be connected by a belt to any available source of power not shown for transmitting rotary motion to the gears or 15 eccentrics —21— and thence through the medium of the connecting rod —22— to the piston —2—.

The valve —12— is oscillated intermittently, one half turn at a time, as the piston 20 approaches the end of its stroke and, although any means may be employed for accomplishing this result, I have shown one of the gears —21— as provided with an eccentric roller-stud —26—, which alternately 25 engages inclining abutments —27— and —28— on a sliding rod —29—. These abutments are disposed at opposite sides of the axis of gears —21— in parallel planes, facing each other, and are spaced apart a 30 distance corresponding substantially to the throw of the eccentric stud —26—, so that as the piston approaches the limit of its stroke, in one direction, the roller-stud —26— will coat with one abutment —28— 35 to move the bar —29— in the same direction and thereby draw the other abutment into the path of movement of the roller-stud to be engaged thereby as the piston moves to the limit of its stroke in the opposite direction. 40 This reciprocal action of the bar —29— is utilized to simultaneously oscillate the valves —12— in the same direction by a suitable mechanism as follows: 45 One of the supporting studs, as —13—, of each valve extends some distance through and beyond the adjacent end head —15— of the valve casing —4— and is provided with a pinion —30— which meshes with a sliding 50 tooth rack —31—, said rack being provided with an additional tooth section —32— meshing with a pinion —33— on a shaft —34—, the latter carrying an additional pinion —35—, which meshes with a similar tooth rack —36— on the sliding bar —29—.

It is now apparent that the movement of the valves is synchronized with that of the piston, the parts of the valve operating mechanism being arranged and adjusted so 60 that when the piston approaches the limit of its stroke, toward one end of the cylinder, the valve at that end of the cylinder will be operated to connect the suction port —6— with the adjacent port —5— while the valve 65 at the opposite end of the cylinder will be

shifted to connect the outlet port —6'— with the corresponding port —5—. Assuming, for example, that the piston —2— is near the right hand end of the cylinder, as shown in Fig. 2, and is being moved back 70 toward the opposite end of the cylinder and that the right hand valve —12— has just been shifted so that the passage —16— of the right hand valve connects the ports —5— and —6—, while the passage —16'— of the left hand valve connects the adjacent ports —5— and —6'—, thus it is clearly apparent, that, as the piston is moved to the left, the liquid will be drawn through the pipes —8— and —7—, port —6—, passage —16— and port —5—, of the right hand end valve into the corresponding end of the cylinder —2—. Then the liquid in advance or at the left of the piston will be simultaneously forced from the cylinder 80 through the corresponding port —5— and thence through the valve passage —16'— and port —6'— into the outlet pipe —7'— whence it may be conducted to any desired locality. A portion of the water which is 90 forced through the outlet will be forced into the air chamber —11—, thereby trapping and compressing the air therein, which operates to additionally expel the water therefrom, as soon as the pressure upon the water 95 by the piston is relieved, thus maintaining a more uniform flow of water through the outlet.

What I claim is:

1. In a piston pump, a valve mechanism 10 comprising a tubular valve casing having a single port in one side and a pair of ports in the opposite side located equi-distant from and at opposite sides of the transverse plane of the single port, and a cylindrical 10 valve having parallel diagonally extending passages therethrough, the inner end of said passages being located in the same transverse plane as the single port and their outer ends disposed in the same transverse planes 11 as the corresponding opposite ports, and means for oscillating said valve one half revolution at a time.

2. In a pump apparatus, a valve casing having an inlet port and an outlet port in one side and an additional port in its diametrically opposite side and an oscillatory valve in the casing having separate parallel passages extending diagonally therethrough and having their inner ends disposed in the same transverse plane coincident with that of the additional port and their outer ends disposed in the same transverse planes as the inlet and outlet ports respectively, and means for oscillating said valve. 12

3. In a double acting piston pump, a cylinder, a piston movable in the cylinder, means for actuating the piston, valve casings at opposite ends of the cylinder, each of said valve casings having an inlet port and an 13

outlet port in one side and an additional port in its opposite side, the additional port communicating with the adjacent end of the cylinder, a pipe connecting the inlet ports of both valve casings, a separate pipe connecting the outlet ports, separate oscillatory valves in the valve casings, each valve having parallel passages extending diagonally therethrough, the inner ends of said passages being disposed in the same transverse plane as the port which communicates with the cylinder, and the outer ends of the passages being disposed in the same transverse planes as the inlet and outlet ports, respectively, and means for simultaneously oscillating said valves.

4. In a pump, a valve mechanism including a valve having passages extending transversely therethrough and terminating at one end in diametrically opposite sides of the valve in the same transverse plane.

5. In combination with a cylinder, a piston movable in the cylinder, valve casings, one for each end of the cylinder, each valve

casing having an inlet port and an outlet 25 port in one side and an additional port in its diametrically opposite side, the additional port being connected to the adjacent end of the cylinder, oscillatory valves having reduced ends journaled in the ends of their 30 respective casings, each valve being provided with transverse passages therethrough terminating at one end in diametrically opposite sides of the valve and in the same transverse plane as the additional port, and their 35 opposite ends terminating in the same transverse plane as the inlet and outlet ports, respectively, means for reciprocating the piston, and additional means for oscillating both valves intermittently but simultane- 40ously one-half revolution at a time.

In witness whereof I have hereunto set my hand this twenty ninth day of September 1909.

JOHN MERTON DENSON.
